A. H. HANDLAN

lantern

Filed May 14, 1926

FIG. I

FIG. II

INVENTOR
A. H. HANDLAN

BY Cook, McAnally
ATTORNEYS

UNITED STATES PATENT OFFICE.

ALEXANDER H. HANDLAN, OF ST. LOUIS, MISSOURI.

LANTERN.

Application filed May 14, 1926. Serial No. 109,081.

My invention relates particularly to lanterns adapted for use by railroad trainmen, and more especially to the ventilating dome of such lanterns.

It is to be understood that the invention comprehends changes, variations and modifications which come within the scope of the claims hereunto appended.

Fig. I is a side elevation, partly in section, of my improved lantern.

Fig. II is a cross sectional view taken on the line II-II in Fig. I.

The lantern illustrated in the drawings consists of a wire guard frame A, a base ring B in which the oil font is adapted to be seated, a glass globe C, a dome D, and the usual bail E (only partly shown). The upper portion of the globe C is held by a plate F which is so mounted as to be capable of a lateral shifting motion to accommodate itself to any irregularity in the position of the globe. G is a spring located between the upper part of said plate F and the inside top of the dome D by which tension is placed 25 on said plate to securely hold said globe in position.

1 designates a wind-deflecting device mounted in the upper central interior portion of the dome D and consisting of two 30 hollow frusto-conical members, the inner 2 and the outer 3, respectively. The member 2 is fitted within the member 3 and spaced apart therefrom and secured to said member 3 by suitable connecting bars 4. The members 2 and 3 are arranged with the tapered ends extending upwardly, as clearly shown in Fig. I. The dome D is provided with a bead 5 against which the outer edge of the member 3 at its largest diameter is adapted 40 to contact to prevent the deflecting device from being pushed up too far and thereby be improperly mounted in said dome. The said dome is also provided with a series of ventilating holes 6 which provide for both 45 ingress of air to support combustion in said lantern and egress of heated air.

When my improved lantern is in service air which enters through the holes 6 in the dome D largely passes on through said dome, 50 but a sufficient amount is permitted to enter into the globe C to support combustion of the light (which is maintained above the wick-holder H in dotted outline in Fig. I). Air inlet holes 7 are also provided in the base ring B, as is ordinarily found in this style 55 of lantern.

Considerable difficulty has been encountered in providing a lantern for railway service within which there may be maintained a substantially uniform flame under 60 the widely diverse conditions encountered. The lantern is sometimes used within a car where there are no drafts; it is sometimes carried in such a way that it is subjected to very slight drafts; sometimes it is exposed to a 65 breeze of high velocity, owing not only to the movement of the air but to the movement of the train in a direction opposite to that in which the wind is blowing; it is also subjected to severe tests in signaling involving 70 rapid changes of angular position with reference to the vertical, and when carried on the top of a rapidly moving train may be inclined forward owing to the stooping posture of the user. It has been found in practice 75 that the lantern which will endure the action of a high wind may have its flame smothered when there is no external movement of air, and again, unless properly made, the light may be extinguished by the action 80 of slowly moving air currents, although it will be maintained either in a high wind or when there is no movement of air whatever. To insure good combustion when the wind is not blowing the dome must be well ventilated 85 to permit the vapors to freely escape. Such ventilation, however, permits air to enter the dome freely when the wind is blowing, and these air currents may either blow out the light or check the outflow of 90 vapors and thus smother it.

In my improved lantern air currents entering the holes 6 are prevented by the deflecting device 1 from being directed downwardly upon the flame, but striking the outer 95 face of the first of the deflecting members 3 some of said air will be broken up and deflected upwardly and thence downwardly along the inner surface of the globe C and thus away from the flame. These downwardly directed currents will reach the flame laterally and stimulate combustion and will also tend to force the vapors upwardly at the opposite side of the globe. The deflecting devices, being substantially edgewise to the 100 upward movement of the vapors, present practically no obstacle to their free egress, even when the draft is not thus stimulated. Most of the air striking the outer deflecting member 3, after passing downwardly adjacent 110 to the wall of the globe, passes out through the peripheral apertures 7, slightly below

the bottom of the globe C, substantially unobstructed. Any surplus amount of air that might escape the outer deflector 3 strikes the inner deflector 2, which also cause practically all of said surplus air to move downwardly and outwardly and thereby reach the peripheral apertures 7 without entering directly the central portion of the globe C.

I claim:

1. A lantern having a perforated dome, a globe, a seat for the bottom face of the globe, a globe holder comprising an annular portion arranged transversely of the lantern, means for maintaining the globe holder in engagement with the globe, an annular housing secured to the dome and enclosing the marginal edge portion of the annular portion of the globe holder, and a plurality of horizontally alined frusto-conical wind deflecting members mounted within the dome and adapted to direct wind entering through the perforations downwardly into the interior of the globe, and outwardly into the space between the annular portion of the globe holder and the enclosing portion of the annular housing.
2. A lantern having a perforated dome, a globe, a seat for the bottom face of the globe, a globe holder provided with means for urging it normally in engagement with the globe, said globe holder including an annular portion arranged transversely of the lantern, an annular housing approximately cup-shaped

in cross section secured to said dome and enclosing the marginal edge portion of the annular portion of the globe holder, said housing being of greater diameter than the globe holder whereby a space is left between the outer marginal edge of the globe holder and the annular housing, and a unitary wind deflecting member mounted within the dome and adapted to divide into two streams air entering through the perforations, and to direct one stream downwardly into the globe and the other stream outwardly in the direction of the space between the annular housing and the marginal edge of the globe holder.

3. A lantern having a perforated dome, a globe, a seat for the bottom face of said globe, a globe holder including an annular portion arranged transversely of the lantern, a housing secured to the dome and enclosing the annular portion of the globe holder, the diameter of the housing being greater than the diameter of the annular portion whereby an opening is provided between the globe holder and the housing, and a unitary wind deflecting member mounted within the dome for dividing into two streams air entering through the perforations, and for directing one stream downwardly into the globe and the other stream outwardly in the direction of the housing.

In testimony that I claim the foregoing I hereunto affix my signature.

ALEXANDER H. HANDLAN.
